PORTABLE EMPLACEMENT FOR MACHINE GUNS

Royal B. Lord, Fort Riley, Kans.

Application September 27, 1940, Serial No. 358,694

6 Claims. (Cl. 89—36)

(Granted under the act of March 3, 1883, as amended April 30, 1928; 370 O. G. 757)

This invention described herein may be manufactured and used by or for the Government for governmental purposes, without the payment to me of any royalty thereon.

This invention relates to a portable emplacement for machine guns and the primary object thereof is to provide a device of this character having fabricated parts which may be readily transported to a strategic position and readily assembled for defense against an enemy's artillery and infantry attack and also readily disassembled for transportation and assembly at other strategic positions.

Another object of the invention is to provide an armored portable emplacement for machine guns of such a character that additional armor may be readily added thereto to increase the thickness thereof for protecting the operating personnel of the machine guns against all infantry weapons, the 75 mm. artillery gun, and fragmentations of heavy shells or bombs and also assembled in such a manner as to resist the crushing effect of heavy tanks.

Another object of the invention is to provide a fabricated portable emplacement for machine guns including firing ports or a bombproof "pillbox" with or without the firing ports which may be readily demountable to flat plates and sections easily nested, requiring a small amount of space when disassembled, which may be stored indefinitely without deterioration, readily transportable from place to place, which is substantially cheap in construction, designed in such a manner as to preclude obsolescence, and provided with universal mounts for the machine guns which are adapted to permit the machine guns to have the maximum field of fire from the ports without any detrimental dead space.

Briefly stated, the fabricated portable emplacement or bombproof "pillbox" is constructed on the basic principle of a laminated box-like structure adapted to be partially buried in the ground and having lapped end joints or edges and interchangeable side walls containing elongated firing ports, also interchangeable upper side cover plates, containing elongated apertures registering with the firing ports in the side walls, vertical angle bars bolted to the side walls and to the upper side cover plates, interchangeable upper and lower firing port cover supporting members 50 detachably bolted to the side walls and side cover plates, port covers slidably mounted in the cover supporting members, a central beam supported by certain of the upper port cover supporting members, removable armor top cover sections resting

on and supported by said beam, the upper cover supporting members and the upper ends of the angle bars, and universal gun mounts mounted on said side walls and adapted to permit machine guns mounted thereon to have a maximum field of fire through the firing ports.

With the above and other objects and advantages in view the invention consists of certain features of construction and operation of parts

10 which will hereinafter appear and in which:

Fig. 1 is a perspective assembly view of the improved fabricated portable armored emplacement or bombproof "pillbox" including a removable armor top covering, firing ports, and machine gun barrels projecting from certain of the firing ports, one of the firing ports being closed and illustrating the emplacement partially buried in the ground;

Fig. 2 is a top view of the emplacement with 20 the armor top covering and machine guns removed therefrom and exposing a plurality of universal mounts for the machine guns positioned beneath the firing ports;

Fig. 3 is an enlarged top view of one of the 25 universal mounts including a portion of a side wall and upper side cover plates of the emplacement taken on the line 3—3 of Fig. 2;

Fig. 4 is a partial side view of Fig. 3 and illustrating the universal mount adjustably mounted 30 on a side wall and showing the relative position of the universal mount with respect to a firing port;

Fig. 5 is an enlarged vertical sectional view of the emplacement taken on the line 5—5 of Fig. 2 35 and illustrating the manner of slidably supporting a pair of port covers for a firing port, with the pair of port covers shown in an open position with respect to the firing port;

Fig. 6 is an enlarged vertical sectional view of 40 the emplacement taken on the line 6—6 of Fig. 1 showing a side wall having its firing port closed by a pair of port covers locked in a closed position and a door slidably mounted on the side wall providing means of access from and to the emplacement;

Fig. 7 is a diagrammatic view illustrating the 45 horizontal field of fire which may be attained by machine guns through the firing ports when mounted on the universal mounts;

Fig. 8 is a diagrammatic view illustrating the 50 vertical field of fire which may be obtained by the machine guns through the firing ports.

Referring more particularly to Fig. 1 of the drawings, 1 designates generally the level of the earth in which is dug an excavation 2 having a

trench 3 leading to the improved emplacement indicated generally by A, with barrels 4 of machine guns projecting outwardly therefrom.

The emplacement or bombproof "pillbox" A is constructed of fabricated interchangeable parts of any suitable material such as heavy steel armor of any suitable size and thickness, and comprises a plurality of interchangeable base or side wall plates or members 5 and 5' which are adapted to partially fit into the excavation 2 and to provide exposed portions on the upper sides thereof. The interchangeable base plates 5 and 5' are assembled to provide a vertically extending rectangular or box-like structure having lapped end joints or edges 6 with one edge of one of each of the plateslapping over one edge of another plate and with one inner edge of a plate abutting against the inner surface of another plate or in other words the plates are symmetrically arranged in pairs with the diagonally opposite ends of one pair of plates abutting diagonally opposite ends of another pair. These interchangeable base plates 5 and 5' are all of the same size and shape and are held in an assembled position by means of vertically extending interchangeable heavy structural angle members or bars 7, one of each of which is provided on one of each of the inner corners of the base plates and bolted thereto by bolts 8 and 8' which extend through vertically aligned holes provided in the angle bars and base plates 5 and 5' and held in position thereon by nuts 9. One of the base plates 5' is provided with an opening 10 normally closed by a door 11 adapted to slidably operate on supporting members 12 suitably secured to the base plate 5', such as by being welded thereto, as more particularly illustrated in Fig. 6, the said door opening into the trench 3 and providing means of access from and to the emplacement A.

The exposed upper side portions of the base plates 5 and 5' are provided with central elongated firing ports 13 and mounted on the outer exposed upper side portions of the base plates are a plurality of interchangeable side cover plates 14 preferably of a greater thickness than the base plates and having elongated apertures 15 therein which register with the firing ports 13 in the base plates, whereby laminated firing ports are provided in the emplacement. The upper side cover plates 14 are illustrated as being in pairs and arranged around the exposed upper surface of the base plates to provide lapped end joints or edges with diagonally opposite ends of one pair of side cover plates abutting diagonally opposite ends of another pair. These upper side cover plates 14 are detachably bolted to the outer exposed upper side portions of the base plates by the bolts 8' which secure the upper portions of the base plates to the heavy angle bars 7. Any suitable number of the upper side cover plates 14 may be added to the structure without any change in design except for providing longer bolts 8' which secure them to the upper portions of the base plates and the angle bars 7. The ends of the heavy structural angle members or bars 7 terminate adjacent to the upper and lower edges of the base plates and are provided with triangular shaped supporting end members 16 for a purpose which will hereinafter appear.

The elongated firing ports 13 in the base plates 5 and 5' are closed by means of interchangeable inside port covers or slides 17, one pair of port covers 17 being used for each firing port and adapted to overlap at their inner ends when closed to prevent leakage of lead. The port covers 17 are adapted to slidably operate in interchange-

able heavy upper and lower port cover supporting members 18 and 18' respectively which are detachably mounted on the inner surface of the base plates 5 and 5' closely adjacent to the upper and lower edges of the firing ports 13 by means of bolts 19 which extend, through aligned holes provided in the cover supporting members 18 and 18', base plates 5 and 5', and the upper side cover plates 14 where they are secured thereto by means of nuts 20.

Each of the interchangeable upper and lower port cover supporting members 18 and 18' respectively, is provided with a central recess 21 on one of the side edges thereof which does not engage the port covers 17, as more particularly illustrated in Figs. 5 and 6. Fitting into the recesses 21 of any two of the upper cover supporting members 18 are the ends of a central supporting beam or heavy structural T-support 22 including a horizontally extending portion 23 and a vertically extending portion 24, the horizontally extending portion 23 of the T-support 22 having a thickness equal to the depth of the recesses 21 in the port cover supporting members, whereby the upper surface thereof is flush with the upper surface of the port cover supporting members, and the end members 16 on the angle bars 7 and is of a less width than the recesses 21 to provide free movement of the supporting beam 22 therein for a purpose which will hereinafter appear. In order to lock each pair of port covers 17 in a closed position a pivotably mounted catch 25 is provided on one of the port covers which is adapted to engage a projection 26 provided on the other port cover of the pair as illustrated in Figs. 5 and 6.

To close the top end of the emplacement A two removable armor plate bombproof cover sections 27 are provided which are adapted to seat on and be supported by the horizontal portion 23 of the supporting beam 22, the heavy upper port cover supporting members 18 and the triangular shaped end members 16 on the upper ends of the vertically extending bars 7. The top cover plate sections 27 are of a less width than the upper inner area of the emplacement whereby they may be freely movable therein and are of a thickness to cause the upper surface thereof to be flush with the upper edges of the base plates 5 and 5' and the outer side cover plate 14. By raising the top cover plate sections 27 from the inside the emplacement, mortar or anti-aircraft fire is possible.

The emplacement is provided with a plurality of universal gun mounts indicated generally by B, one for each firing port 13 in the base plates 5 and 5'. The universal gun mounts are adapted to fit the firing parts and are designed to receive and lock the standard base plate of a machine gun. Each of the universal mounts B comprises substantially Z-shaped horizontally arranged angle bars 28 having their outer ends provided with vertically extending elongated slots 29 and adjustably mounted on the base plates 5 and 5' adjacent to the lower edge of the firing ports 13 by bolts 30 which extend through holes provided in the base plates and the vertically extending slots 29 provided on the outer ends of the bars where they are detachably secured in place by nuts 31. On the inner ends of the angle bars 28 is mounted a horizontally extending supporting member 32, which is suitably secured to the angle bars 28 by being welded thereto or the like. Slidably mounted on the supporting member 32 is a gun

carriage 33 including a downwardly extending portion 34 having projecting portions 35 extending therefrom which are adapted to slidably engage the supporting member 32. A horizontal inwardly extending flat portion 36 is also provided on the gun carriage 33. By this construction the maximum use of the firing ports 13 is obtained for permitting guns (not shown) which are adapted to be supported on the universal mounts to horizontally slide to either extremity of the ports and to vertically raise or lower the guns to the top or bottom of the ports with a minimum port area exposed, yet not restricting the field of fire from any port. The .50 caliber machine guns with anti-aircraft type base can be mounted on the universal mounts without change. For the standard tripod mount, a small plate 37 is inserted in each universal mount to hold the front leg of the guns (not shown).

The maximum traverse provided by the firing ports 13 at a horizontal angle for the machine guns when constructed of a size started below is diagrammatically illustrated in Fig. 7 as being 2500 mils or 140.63° and the maximum elevation or depression (vertical angle) is diagrammatically illustrated in Fig. 8, as being 550 mils elevation or 550 mils depression with a total vertical angle for each port of 1100 mils or 61.87° . The small flag-like members 42 indicate the direction of fire.

In a pilot model it has been found satisfactory to make an emplacement which is adapted to allow four feet of the structure to be received by the excavation 2 with a height projecting above the level 1 of the earth approximately 1 foot 6 inches. The vertical target exposed for each base being 6 feet 4 inches by 1 foot 6 inches and the top target being 6 feet 4 inches square. Additional protection and camouflage are easily possible by use of sand bags, or natural cover. If the firing ports 13 are made 8 inches by 24 inches a 360° observation and field of fire is permitted with no detrimental dead space 43 indicated in Fig. 7, and the fire from machine guns in any two adjacent firing ports 13 on the emplacement will intersect within a distance of less than 6 feet from the emplacement.

By eliminating the universal mounts B for the machine guns from the emplacement A a portable low-cost steel bombproof shelter may be provided with or without ventilating ports. Should the bombproof shelter be provided without ventilating ports the base plates 5 and 5' and the side cover plates 14 would be constructed without the firing ports 13 and the apertures 15 respectively, thereby eliminating the necessity for the inside port covers 17 and the lower port cover supporting members 18'. It is therefore within the scope of this invention to provide a portable bombproof shelter constructed in the manner as described above with or without ventilating ports.

The structure above described can be transported in trucks of normal body size. The heavier top-plate sections of which there are two, will require little handling as they are not bolted to the structure. The plates used in the structure cannot be damaged by rough handling and may be skidded behind tractors if conditions prescribe the use of the emplacement in normally inaccessible locations. If penetration of the emplacement occurs in the field the upper side cover plates 14 on the upper outer

portions of the base plates 5 and 5' not exposed to attack can be used to increase the thickness of the metal on the sides exposed to the enemy, therefore by the use of this design obsolescence is precluded.

It will thus be seen that there is herein provided a novel and useful form of portable emplacement for machine guns or bombproof "pillbox" which is designed as a whole as a box girder to offer the maximum strength of the materials used to resist the separated blows of infantry and artillery weapons and the crushing effect of heavy tanks. Transmission of side blows is through heavy structural angle bolts to the plates, materials produced for commercial practice only are required and fabrication is possible in any steel manufacturing or fabrication plant. No special tools are required to fabricate the component parts of the emplacement and the design incorporates the maximum of interchangeability and standardization. Even though there has herein been shown certain features of construction and operation of parts, it is nevertheless to be understood that various changes may be made therein without departing from the spirit or scope of the invention.

Having described my invention, what I claim as new and wish to secure by Letters Patent is:

1. A machine gun emplacement comprising a fabricated structure adapted to be partially buried in the ground and having interchangeable base plates containing firing ports, interchangeable cover supporting members mounted on said base plates, port covers slidably mounted on said cover supporting members, and adapted to be operated to open and close said firing ports in the base plates; a central supporting beam adapted to seat on certain of said cover supporting members, bombproof cover section plates provided on the upper portions of said base plates and adapted to be partially supported by said beam and certain of said cover supporting members and interchangeable upper side cover plates mounted on the exposed upper side portions of said base plates, said side cover plates having apertures therein registering with the firing ports in said base plates.

2. A machine gun emplacement comprising a fabricated structure adapted to be partially buried in the ground and having interchangeable base plates containing elongated firing ports, angle bars bolted to said base plates, interchangeable upper and lower port cover supporting members mounted on said base plates, port covers slidably mounted on said cover supporting members and adapted to be operated to open and close the firing ports in said base plates, a central supporting beam adapted to seat on certain of said upper cover supporting members and removable bombproof top cover section plates adapted to rest on and be supported by said upper cover supporting members, the central beam and upper ends of said angle bars.

3. A machine gun emplacement comprising a fabricated structure adapted to be partially buried in the ground and having interchangeable base plates containing elongated firing ports, angle bars detachably secured to said base plates, interchangeable upper and lower port cover supporting members detachably secured to said base plates, recesses formed in said port cover supporting members, port covers slidably mounted on said port cover supporting members and adapted to be operated to open and close the firing ports in said base plates, a central support-

ing beam adapted to seat in the recesses in certain of said upper port cover supporting members, removable bombproof cover section plates provided on the upper portion of said base plates, said bombproof cover section plates adapted to rest on and be supported by the upper port cover supporting members, the central beam and said angle bars and interchangeable upper side cover plates mounted on the exposed upper side portions of said base plates, said side cover plates containing apertures in alignment with the firing ports in said base plates.

4. A machine gun emplacement comprising a fabricated structure adapted to be partially buried in the ground and having interchangeable base plates containing firing ports, angle bars bolted to said base plates, interchangeable upper and lower port cover supporting members bolted to said base plates adjacent to the upper and lower edges of said firing ports, port covers slidably mounted on said port cover supporting members and adapted to be operated to open and close the firing ports in the base plates, a central supporting beam adapted to movably seat on certain of said upper port cover supporting members, removable bombproof section plates provided on the top portions of said base plates and adapted to rest on and be supported by said upper port cover supporting members, the central beam and upper ends of said angle bars, interchangeable upper side cover plates mounted on the exposed upper side portions of said base plates, said side cover plates containing apertures registering with the firing ports in said base plates, and gun supporting members vertically and horizontally adjustably mounted on said base plates adjacent to said firing ports.

5. A fabricated frame structure of such size as to provide a bombproof shelter and adapted to be partially buried in the ground, said structure including interchangeable angle bars, having upper and lower end members provided thereon, interchangeable steel base plates with lapped ended edges bolted to said angle bars, interchangeable upper steel side cover plates with lapped ends bolted to the exposed upper side portions of said base plates and to said angle bars, a central supporting beam mounted on upper portions of certain of said base plates and removable bombproof armor plate sections provided on the upper portion of said base plates and adapted to rest on and be supported by said central beam and the upper end members of said angle bars.

6. A machine gun emplacement comprising pairs of interchangeable base plates containing firing ports, said base plates symmetrically arranged, with diagonally opposite ends of one of said pairs of base plates abutting diagonally opposite ends of another pair, supporting members mounted on said base plates, port covers slidably mounted on said supporting members and adapted to be operated to open and close said firing ports, side cover plates mounted on said base plates, said side cover plates having apertures therein registering with the firing ports in said base plates, a beam mounted on certain of said port cover supporting members, and bombproof top cover section plates adapted to seat on said beam and certain of said port cover supporting members.

ROYAL B. LORD.
